UNITED STATES PATENT OFFICE.

VIRGINIA M. HOLLYDAY, OF CARROLL, MARYLAND.

HAT OR BONNET HOLDER FOR TABLES AND WARDROBES.

SPECIFICATION forming part of Letters Patent No. 381,016, dated April 10, 1888.

Application filed June 20, 1887. Serial No. 241,895. (No model.)

To all whom it may concern:

Be it known that I, VIRGINIA M. HOLLYDAY, of Carroll, in the county of Baltimore and State of Maryland, have invented certain new and useful Improvements in Hat or Bonnet Holders for Tables and Wardrobes, of which the following is a specification, reference being had to the accompanying drawings, and to the letters of reference marked thereon.

10 The nature and object of my invention will be fully set forth in the following specification and claim.

In the drawings, Figure I is a perspective view of my invention. Figs. II and III are 15 views (the former in section) of a part of my invention detached, and Fig. IV shows a modification.

Similar letters of reference indicate similar parts in the respective figures.

20 A A are tracks formed of metal so bent as to form T-shaped grooves a, and B B are standards adapted to slide therein. The tracks can be arranged to cross each other, as shown, and as many of them may be provided as circumstances may require. At the points where 25 the tracks cross each other the upper flanges, a', are cut away, so as to allow the standards B to slide from one track into any cross-track.

At the crossing-points the tracks are held together by plates C, secured to them by soldering or otherwise. These plates are provided 30 with holes, in order that the tracks may be fastened to a table or other surface by nails or screws. Plates or feet D, having holes, are 35 placed at the ends of the tracks for the same purpose.

The standard B consists of a rod, b, and a tube, b', adapted to slide thereon. The tube carries at its upper end a plate, D', forming a 40 rest for the hat or bonnet. On the lower end of the rod b is a flanged thimble, b'', provided with a T-shaped lug or projection, b'', adapted to fit in the T-shaped grooves of the tracks.

The tube b' is furnished with slots d, through 45 which the spring d' in the rod b is adapted to project, and thus allow the supporting-plate D' to be adjusted to different heights. The

slot d'' and pin d''' are for the purpose of preventing the tube from being pulled entirely off the rod.

Fig. IV shows a table having T-shaped grooves formed in the top thereof, in which the standards B can slide.

My invention will be found exceedingly useful to milliners, as, the standards being adjustable both in position and height, any-sized hat or bonnet can be supported, and by placing the standards carrying the hats with the broadest brims lower than the others many more hats can be supported in the same space 60 than heretofore.

I do not limit myself to the relative widths of the two parts of the groove as shown in the drawings, as in some cases the horizontal part of the groove may be extended and the T-shaped projection enlarged, as shown in Fig. II. With this change the standard is made much steadier. I have shown the standards as extending upward; but it is evident that the track can be formed on the under side of the 70 shelf in a wardrobe, in which case the standards would be pendent. Further, the base of the standards could be made of such size and shape as to hold the bonnets and hats without the track, and under such circumstances the 75 track would be dispensed with, but the extensibility of the standards would be maintained.

Having described my invention, I claim—
In an adjustable standard for supporting 80 hats or bonnets, the combination, with a rod having at its upper end a pin and a spring, of a tube adapted to slide on said rod, said tube being provided with a slot extending nearly 85 its entire length, into which the pin on the rod enters, and also with a series of slots through which the said spring is adapted to project, and a supporting-plate secured to the upper end of said tube, substantially as specified.

VIRGINIA M. HOLLYDAY.
